OTHER PUBLICATIONS Samsung Stackable Dryer <https://www.lowes.com/pd/Samsung-4-cu-ft-Stackable-Electric-Dryer-White/1001061396> (Year: 2017).*Primary Examiner — Michelle E. Wilson*Assistant Examiner* — Richard E Yenchesky*(74) Attorney, Agent, or Firm* — NSIP Law**(57) CLAIM**

I claim the ornamental design for a dryer, as shown and described.

DESCRIPTION

FIG. 1 is a front perspective view of a dryer showing my new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is an enlarged view of the encircled portion of FIG. 1;

FIG. 9 is an enlarged view of the encircled portion of FIG. 2;

FIG. 10 is an enlarged view of the encircled portion of FIG. 5; and,

FIG. 11 is an enlarged view of the encircled portion of FIG. 7.

The broken lines in the figures show portions of the dryer which form no part of the claimed design.

The dot-dash broken lines encircling portions of the claimed design that are illustrated in enlargements form no part of the claimed design.
